Primary Examiner — Brett Miller*Assistant Examiner* — Rani J Abdallah(74) *Attorney, Agent, or Firm* — Knobbe Martens Olson & Bear, LLP**CLAIM**

The ornamental design for a cap with tamper-evident ring, as shown and described herein.

DESCRIPTION

FIG. 1 is a top perspective view of a cap with tamper-evident ring embodying the new design.

FIG. 2 is a bottom perspective view thereof.

FIG. 3 is a front view thereof.

FIG. 4 is a rear view thereof.

FIG. 5 is a first side view thereof.

FIG. 6 is a second side view thereof.

FIG. 7 is a top view thereof; and,

FIG. 8 is a bottom view thereof.

All features in broken lines are for the purpose of illustrating environmental structure and form no part of the claimed subject matter.

1 Claim, 5 Drawing Sheets---
